UNITED STATES PATENT OFFICE.

LOUIS JULES NOËL, OF EPERNAY, FRANCE.

APPARATUS FOR PURIFYING INDUSTRIAL OILS AND FATS.

1,209,480.

Specification of Letters Patent. Patented Dec. 19, 1916.

Application filed May 14, 1914. Serial No. 838,487.

To all whom it may concern:

Be it known that I, LOUIS JULES NOËL, a citizen of the French Republic, and residing at 18 Rue du Moulin à Vent, Epernay, 5 Marne, France, engineer, have invented certain new and useful Improvements in and Relating to Improved Apparatus for Purifying Industrial Oils and Fats, of which the following is a complete specification.

10 This invention has for its object to provide an improved apparatus for purifying oils, fats and greases which have been used in workshops and factories either for lubricating machinery or parts of machinery, or 15 for other purposes and in the course of which use all kinds of impurities have become incorporated in these oils, fats and greases. Oil, fat or grease rendered impure by such uses is hereinafter referred to as 20 "used oil."

One example of the improved apparatus is illustrated in the accompanying drawing in which:—

25 Figure 1 is a vertical axial section of the entire apparatus with a convenient heating means. Fig. 2 is a cross section on the line 2—2 of Fig. 1.

In the example shown, the improved apparatus consists of a vat or similar vessel *a* 30 for containing the used oil to be purified, having a conical bottom *b* fitted at its lower end with a blow-off cock *c*. This vat or collector *a* for the used oil or grease is closed by means of a lid *d* through which there 35 extends a pipe *e* toward the bottom of the vat, for instance as far as the commencement of the cone *b*. This pipe *e* ends at its upper end outside the vat in a funnel *f*. The cover *d* need not close absolutely airtight. 40 An oil exit pipe *g* extends from the upper part of the cylindrical body of the vat *a*. The vat is inclosed in a casing *h* which forms a jacket *i* for the circulation of hot water around the vat. The water enters through an upper inlet *j* and after 45 circulating passes out through a lower outlet *k*. The heating of this water may be effected in various ways, for instance by utilizing the hot exhaust gases of a gas engine, where 50 the apparatus is set up in a factory or workshop using a gas engine, or by utilizing steam. In the first case there is arranged on the gas exhaust pipe *m*, a small boiler *n* of the shape shown in cross section in Fig. 2 55 arranged astride the pipe *m*. From the upper part of this boiler there extends a ver-

tical pipe *o* which opens into the inlet *j* of the water jacket *h*. From one of the ends of the boiler there extends a pipe *p* which opens into the outlet *k*.

60 For the purpose of filling the boiler the pipe *p* is connected to a water supply pipe *q* by means of a vertical pipe *r* fitted with an expansion vessel *s* and a tap *t*. The pipe *q* is provided with a cock *u* for discharging 65 over the funnel *f*.

To heat the water jacket *i* by means of steam it is sufficient to arrange at the bottom of the casing *h* a steam nozzle *v* to which steam is supplied by a pipe *x*.

70 The operation is as follows: The oils, fats and greases which have been used and which it is desired to purify are collected in the vat *a*. The water jacket *i* is heated as described so as to produce an automatic and 75 continuous circulation of the hot water. The hot water enters the casing *h* at a temperature which is generally about 70 degrees C. and passes out through the outlet *k* at a temperature of about 65 degrees 80 C. The heating is continued for about 36 hours, at the expiration of which all the impurities which have been carried over mechanically by the oil or grease during the lubrication of machinery have become separated, precipitated and collected in the conical bottom *b*. When the purification has 85 been carried far enough, the purified oil is removed by admitting water into the vat *a* through the pipe *e*, whereupon the purified 90 oil will flow out through the pipe *g*. When the vat has been filled with water the blow-off cock *c* is opened and the impurities are 95 discharged therethrough.

The improved apparatus has the advantage of being simply and economically constructed, of being readily kept in working order, and of being reliable and automatic in operation. In particular, it is not liable to become choked with dirt as is the case for 100 instance in apparatus having heating coils which are immersed directly in the liquid or substance to be purified, and in which the impurities have a tendency to be deposited upon said coils, thereby necessitating frequent 105 cleaning.

What I claim is:

An apparatus for purifying oils and fats, comprising a jacketed vat having an oil discharge at its upper end and a sediment 110 discharge in its bottom, a water pipe extending into the vat, a boiler, pipes leading

from the boiler into the upper and lower portions of water jacket of the vat, a water supply pipe adapted to discharge into the pipe of the vat, an expansion vessel connected with the water pipe, and a pipe leading from the expansion vessel and connected with the pipe leading from the boiler to the lower portion of the water jacket.

In testimony whereof I have hereunto set my hand at Paris (France), this second day 1. of May, 1914.

LOUIS JULES NOËL.
